UNITED STATES PATENT OFFICE.

PAUL DE GUARDIA-CALMÈTES, OF CAYEUX-SUR-MER, FRANCE.

APPARATUS FOR THE TRANSFORMATION OF REEDS INTO WOVEN FABRICS SUITABLE FOR THE MANUFACTURE OF CEILING LATH-WORK, BASKETS, RECEPTACLES, AND THE LIKE.

1,373,721.

Specification of Letters Patent.

Patented Apr. 5, 1921.

Application filed October 27, 1920. Serial No. 419,963.

To all whom it may concern:

Be it known that I, PAUL DE GUARDIA-CALMÈTES, engineer, citizen of the Republic of France, residing in Cayeux-sur-Mer, 5 Somme, France, "Villa l'Etoile," have invented certain new and useful Improvements in Apparatus for the Transformation of Reeds into Woven Fabrics Suitable for the Manufacture of Ceiling Lath-Work, 10 Baskets, Receptacles, and the like; and I do hereby declare the following to be a full, clear, and exact description of the invention, such as will enable others skilled in the art to which it appertains to make and 15 use the same, reference being had to the accompanying drawings, and to letters or figures of reference marked thereon, which form a part of this specification.

In the application for patent filed in the 20 name of Guardia-Calmètes the 24th of March, 1920,—Serial No. 368371—was described a method and apparatus for the transformation of reeds into woven fabrics wherein the reeds in the raw state are 25 disposed in a hopper whence they are taken one by one by a distributing wheel which causes them to engage successively and end to end between the peeling, splitting and flattening devices. After these different operations 30 the various lengths of strip thus obtained are joined together by connecting members and wound upon reels which are subsequently employed in connection with the weaving looms.

35 This patent relates to improvements in the disposition of the apparatus, the object of these improvements being to obviate the use of the connecting members employed to join the different lengths of reed strip or 40 band. For this purpose the previously peeled reeds are disposed vertically upon a platform mounted above the loom. The reeds are engaged at the upper and lower parts thereof between suitably spaced cross- 45 pieces disposed upon feed cables actuated by a weight, whereby the reeds are moved forward toward the axis of the weaving loom. The reeds are then separated and spaced in line by special devices which feed them successively between the splitting rollers then 50 between the reed-opening cylinders, and lastly between the flattening cylinders, all three devices being disposed directly above the loom. Upon leaving the flattening cyl-

inders, the bands formed by the flattened 55 reeds are caused to pass within pivoted curved guiding members disposed in quincunx and actuated by the heddles of the loom, in such manner as to obtain, as in the principal patent, two sets of warp portions which are alternately displaced to the 60 right and left after the passage of each woof portion. The reeds are thus fed forward successively and automatically through the preparing devices in such manner as to constitute continuous warp bands which are employed directly in the loom without requiring the use of connecting members, as set forth in the previous application above mentioned. 65

70 The accompanying drawings show the improvements above indicated.

Figure 1 is a side view of the upper part of the loom having disposed above the same the devices for transforming the peeled reeds 75 into two sets of warp bands. Fig. 2 is a side view on a larger scale of the devices for transforming the reeds. Fig. 3 is a front view of the same. Fig. 4 is a plan view of a number of devices for feeding the reeds 80 separately into the transforming devices. Fig. 5 is a plan view of the splitting devices. Fig. 6 is a plan view of the opening cylinders. Fig. 7 is also a plan view of the flattening cylinders. 85

Above the loom proper is disposed a platform 63 having resting thereon the lower end of the previously peeled reeds 1. The reeds have the upper and lower part thereof engaged between the cross bars 64 disposed 90 between the upper and lower feed cables 65, 66. These cables which pass over the guide pulleys 67, 67¹ are connected together in pairs by a clamping member 68. To the lower cables 66 are secured the weights 69 whereby the reeds are caused to advance and to slide upon an inclined platform 70 serving as an extension of the platform 63. The reeds 1 are then separated and spaced apart by the selecting devices consisting of the 95 corrugated elastic plates 71 which are given a reciprocating movement and are disposed upon an inclined plane in such manner that only a single reed can be fed at a time against the vertical guide 72 and between 100 each pair of selecting members. 105

For this purpose the corrugated plates 71 are caused to move alternately in pairs in

opposite directions (Fig. 4) the reeds being thus given a rolling motion whereby they are brought forward; said plates are provided with shanks 73, 73¹ having engaged 5 therein the arms 74, 74¹ secured to the shafts 75, 75¹ which are actuated by the cranks 76, 76¹ mounted upon the shafts 75, 75¹. The cranks 76, 76¹ are connected with the rods 77, 77¹ which are actuated by the cranks 78, 10 78¹ mounted on a shaft 79 carrying the splitting members to be further described.

Above the corrugated plates 71 are disposed the disks 80 provided with elastic blades 81 for taking up and separating the 15 reeds in combination with the corrugated plates 71, and to cause them to descend in front of the guide rollers 82 which press the selected reeds against the vertical guide 72. The shaft 83 carrying the disks 80 is 20 rotated by a chain 84 passing over the gear wheels 85.

The guiding and feeding rollers 82 are constituted by an outer rim connected to the hub by resilient arms in such manner that 25 the reeds are readily allowed to pass through the device irrespectively of their thickness. Each of the reeds drawn along by a guide roller 82 is caused to engage between the individual splitting devices constituted by 30 the circular knife 86 disposed between the rollers 87 and coöperating with a grooved roller 88 (Fig. 5) mounted in a forked support 89 the rod whereof 90 is submitted to the action of the spring 91, thus permitting 35 the reeds to pass between the knives 86 and the rollers 88 irrespectively of their thickness.

The split reeds then engage between the 40 rollers 92 and 93 provided for the purpose of opening the same (Fig. 6). The rollers 92 are mounted upon a common shaft 94, and the rollers 93 are disposed in the forked supports 89 the rods whereof are submitted to the action of the springs 91 as in the case of 45 the disks 88 of the splitting devices.

The reeds which are thus opened are then brought between the flattening cylinder 95 mounted upon shaft 96 and rollers 97 disposed in the forked supports 89 having 50 spring mounted rods.

Upon leaving the flattening devices, the warp bands 26 are brought within the elastic guideways 98 pivoted at 99 which are actuated by the horizontal heddles of the weaving loom, 29 and 29¹; said guideways are disposed in quincunx in such manner as to divide the warp into two sets which are displaced alternately to the right and left after the passage of each woof portion, as set forth 55 in the above named patent.

The operation of the various devices for preparing the reeds as above described is effected by a shaft 100 which is actuated by the driving mechanism of the loom. For 60 this purpose said shaft carries a bevel gear

101 coöperating with a second bevel gear 102 secured to the shaft 96 of the reed flattening roller 95 which also carries a gear wheel 103 transmitting the movement to the gear 104 mounted on the shaft 94 of the reed opening 70 members 92 through the medium of a gear wheel 105. The gear wheel 104 actuates in turn, by means of gear 106, a gear wheel 107 mounted upon the shaft 79 of the knives 86.

Having now particularly described and 75 ascertained the nature of my said invention and in what manner the same is to be performed, I declare that what I claim is:—

1. An apparatus for the transformation of reeds into woven fabrics suitable for the 80 manufacture of ceiling lath work, baskets, receptacles and the like, constituted by reed preparing devices located above the weaving loom; comprising a platform upon which the reeds are disposed vertically, means for 85 separating and spacing in line the reeds, means for feeding the said reeds, means for splitting, opening and flattening the same, and a device for feeding directly the warp bands into the weaving loom. 90

2. Apparatus for the transformation of reeds into woven fabrics, comprising a platform upon which the reeds are disposed vertically, a fixed member to guide the reeds, cables provided with cross pieces and actuated by a weight for feeding the said reeds, means for separating and spacing in line the reeds, means for splitting, opening and flattening the same, and a device for feeding 95 directly the warp bands into the weaving 100 loom. 100

3. Apparatus for the transformation of reeds into woven fabrics, comprising a platform upon which the reeds are disposed vertically, cables provided with cross pieces and 105 actuated by a weight, corrugated feeding plates, means for communicating reciprocating motion to said plates, an inclined plane upon which the reeds advance, a fixed member to guide the reeds, means for splitting, opening and flattening the same and a device for feeding directly the warp bands into the 110 weaving loom.

4. Apparatus for the transformation of reeds into woven fabrics, comprising a platform upon which the reeds are disposed vertically, cables provided with cross pieces and actuated by a weight, corrugated feeding plates, means to communicate reciprocating motion to said plates, a fixed inclined plane 115 upon which the reeds advance, a fixed member to guide the reeds, means for splitting, opening and flattening the same and a device for feeding directly the warp bands into the 120 weaving loom. 125

5. Apparatus for the transformation of reeds into woven fabrics, comprising a device for receiving vertically the reeds, means for feeding individually the same, rollers mounted upon a common shaft, rotary knives 130

disposed between said rollers, other rollers mounted in elastic supporting members, means for opening and flattening the reeds and a device for feeding directly the warp bands into the weaving loom.

6. Apparatus for the transformation of reeds into woven fabrics, comprising a device for receiving vertically the reeds, means for feeding individually the same, means for splitting lengthwise the reeds, solid rollers mounted on a common shaft and grooved rollers elastically supported for opening the split reeds, means for flattening said reeds and a device for feeding directly the warp bands into the weaving loom.

7. Apparatus for the transformation of reeds into woven fabrics, comprising a device for receiving vertically the reeds, means for feeding individually the same, means for

splitting lengthwise the reeds, means for opening same, a cylindrical roller mounted upon a shaft and cylindrical rollers elastically supported for flattening the split and opened reeds, and a device for feeding directly the warp bands into the weaving loom.

8. Apparatus for the transformation of reeds into woven fabrics, comprising a device for receiving vertically the reeds, means for feeding individually the same, means for splitting lengthwise the reeds, means for opening and flattening the said reeds, curved guiding members, and horizontal beams of the weaving loom actuating said members to feed the warp constituted by the reed bands into the loom.

In testimony that I claim the foregoing as my invention I have signed my name.

PAUL DE GUARDIA-CALMÈTES.
